CONTOUR CHAIR WITH HINGEDLY
MOUNTED BACK PAD

Leo C. Malco, Long Beach, Calif.

Application April 26, 1952, Serial No. 284,577

5 Claims. (Cl. 155—105)

1

This invention relates to a contour chair which has a back pad which normally rests against the padded back portion of the chair and the back pad may be moved from its normal resting position against the back of the chair to a position elevated from the seat of the chair and forwardly of its normal position. In this manner a contour chair may be provided in which the legs of the user are elevated as he reclines in the chair.

An object of my invention is to provide a contour chair in which the back pad of the chair is mounted on the side arms and these side arms in turn are pivotally attached to the frame of the chair so that the back pad may be swung forwardly from its normal position and also in a position above the level of the seat of the chair.

Another feature of my invention is to provide a novel contour chair of the character stated, in which the back of the chair is padded as well as the auxiliary back so that either or both may be used with comfort.

Other objects, advantages and features of invention may appear from the accompanying drawing, the subjoined detailed description and the appended claims.

In the drawing—

Figure 1 is a side elevation of my contour chair with the auxiliary back pad in position resting against the back of the chair.

Figure 2 is a side elevation of the same showing the auxiliary back pad swung forwardly and elevated above the seat of the chair.

Figure 3 is a side elevation of a slightly modified form of contour chair in which the back pad also includes a portion of the seat of the chair.

Figure 4 is a side view of the modification shown in Figure 3, and with the auxiliary back pad swung forwardly.

Figure 5 is a side elevation of still another modified form of contour chair in which the auxiliary back pad is slidably and hingedly mounted.

Figure 6 is a side elevation of the modification shown in Figure 5 and with the auxiliary back pad swung forwardly.

Figure 7 is a side view of one of the hinges employed in my contour chair.

Figure 8 is a top plan view of one of the hinges.

Referring more particularly to the drawing, the numeral 1 indicates the usual chair frame or base which also includes the usual supporting legs 2. The seat portion 3 of the chair is padded or upholstered in the usual and well known

2

manner. A back 4 may be either fixedly or pivotally attached to the frame 1, as shown at 5. The front surface of the back is padded or upholstered to provide a comfortable surface upon which to lean when this back is being used alone without the auxiliary pad.

As shown in Figures 1 and 2, an auxiliary pad 6 conforms in general contour to the back 4 and normally rests against this back, as shown in Figure 1. The auxiliary pad 6 is upholstered or padded so that it also provides a comfortable surface upon which to lean or rest. Normally, the auxiliary pad 6 is resting against the chair back 4 and extends the full length of this back from top to bottom, or substantially so.

When it is desired to use the chair as a contour type, the following structure is employed:

The side arms 7 are fixedly secured at one end to the back pad 6. At the other end the arms are pivotally secured to the frame 1 of the chair as shown at 8. This hinge is preferably of the adjustable or friction type, including a central pivot bolt 9, a nut 10, which screws on to this bolt, the bolt clamping the plates or rings 11 against the hinged arms 12, thus holding the hinge in any desired adjusted position. When the chair is used as a contour chair, the pad 6 is swung forwardly by pivoting the arms 7 around the pivots 8 and the hinges are clamped to secure the desired position of the pad 6 which now becomes a foot or leg rest.

When not in use as a contour type of chair, the back pad 6 rests against the back 4 and the arms 7 are then used in a normal manner.

In the modification shown in Figures 3 and 4, the back pad 13 also includes a lower portion 14 which is a part of the seat of the chair. The portion 14 is the rear section of the chair seat when the pad 13 is in normal position, resting against the back 4. The back 13 is again fixedly attached to the side arms 15 and these side arms are pivotally mounted on the frame 1 of the chair by the pivots 16, which may be of the same construction as the hinge or pivot 8. When the chair is used as a contour type, the arm 15 with its attached back or auxiliary pad 13 is swung forwardly, as shown at 14, thus providing an elevated rest for the feet or legs of the user. In normal position, the front surface of the auxiliary pad 13 is upholstered or padded to provide a comfortable surface against which to rest.

In the modification shown in Figures 5 and 6, the auxiliary back pad 17 is pivotally secured to the frame 1 of the chair, as shown at 18, and this hinge or pivot 18 is slidably horizontally in a slot

19 formed in the frame 1 of the chair. When it is desired to use the chair as a contour type, the parts are arranged as shown in Figure 6, the back pad 17 is moved forwardly in the slot 19 and is then pivoted forwardly to a further extent by adjusting the hinge or pivot 18. Again, the hinge or pivot 18 can be of the clamping type as shown in Figures 7 and 8.

Having described my invention, I claim:

1. A contour chair with hingedly mounted back pad comprising a frame, legs depending from the frame, a padded seat on the top of the frame, a back rising from the frame, the front of the said back being padded, an auxiliary pad resting against the back in one position thereof, an arm attached to the auxiliary pad on each side thereof, the outer end of said arms being pivotally mounted on said frame, said auxiliary pad being movable forwardly of the back of the chair and in a plane above the seat of the chair.

2. A contour chair with hingedly mounted back pad comprising a frame, legs depending from the frame, a padded seat on the top of the frame, a back rising from the frame, means pivotally attaching the back to the frame, an auxiliary pad resting against the back in one position of the pad, an arm fixedly attached to each side of the auxiliary pad, and means pivotally securing the outer end of each of the arms to the frame of the chair.

3. A contour chair with hingedly mounted back pad comprising a frame, legs depending from the frame, a padded seat on the top of the frame, a back rising from the frame, means pivotally attaching the back to the frame, an auxiliary pad resting against the back in one position of the pad, an arm fixedly attached to each side of the auxiliary pad, and means pivotally securing the

5 outer end of each of the arms to the frame of the chair, said last named means including an adjustable and clamping hinge whereby the auxiliary pad may be variably adjusted relative to the back and the seat of the chair.

10 4. A contour chair with hingedly mounted back pad comprising a frame, legs depending from the frame, a padded seat on the top of the frame, a back, means hingedly securing the back to the frame, the front of said back being padded, an auxiliary back pad, said auxiliary back pad extending partially across the seat of the chair and forming the back of said seat in one position of the auxiliary pad, an arm secured each side of the auxiliary pad and means pivotally securing each of the arms to the frame of the chair.

15 5. A contour chair with hingedly mounted back pad comprising a frame, legs depending from the frame, a padded seat on the top of the frame, a back rising from the frame, the front of said back being padded, an auxiliary pad resting against the back in one position of said pad, and means mounting said auxiliary pad on the frame for both pivotal and horizontal movement relative to said frame.

20 25 LEO C. MALCO.
